UNITED STATES PATENT OFFICE.

WALTER F. SMITH, OF PROVIDENCE, RHODE ISLAND, ASSIGNOR TO BROWN & SHARPE MANUFACTURING COMPANY, OF PROVIDENCE, RHODE ISLAND.

CUTTER CLEARANCE GAUGE.

Application filed October 17, 1923. Serial No. 669,164.

To all whom it may concern:

Be it known that I, WALTER F. SMITH, a citizen of the United States, residing at Providence, in the county of Providence and State of Rhode Island, have invented new and useful Improvements in Cutter Clearance Gauges, of which the following is a specification.

This invention relates to certain new and useful improvements in cutter clearance gauges and the primary object thereof, is to provide a gauge of this type which is adaptable for use with cutters of varying diameters and more specifically without the manipulation of screws or nuts or other fastenings.

A further object of the invention, is to provide a gauge which is of simple and economical construction, involving a minimum of parts that can be easily assembled and operated.

A still further object of the invention is to provide a gauge which has a double-ended gauge point readily removable for substitution by another point having different angles for measuring different angles of clearance, so as to make the gauge of wide use.

In the drawings:

Figure 1, is a front elevation of the invention;

Figure 2, is a side edge elevation thereof; and

Figure 3, is a plan view of the slide.

In proceeding in accordance with the present invention a substantially and preferably integrally formed Y-shaped member is employed having divergent arms 1 and 2 and a central arm 3.

The outer end portions of the arms 1 and 2 are preferably tapered and have rounded points or free ends.

A guide 4 is attached to the central arm 3 and is composed of a plate having a central channel 5, the latter facing the arm 3 and forming an opening in conjunction with the latter. Screws 6 secure the sides of the plate to the arm 3.

A slide 7 is movably received within the opening and extends beyond the outer ends of the arm 3 and the guide and beyond the points of juncture of the arms 1 and 2. The slide, 7 has its front and rear faces at its ends oppositely tapered or beveled and formed with angular gauge faces or edges

8-9 and 8'-9' the latter faces or edges being of different angular relation so as to afford a different clearance readings accordingly. The tapered faces of the slide facilitate reading and with the contracted or curved side portions thereof enable the slide to be more readily introduced into the ends of the opening conjointly formed by the guide 4 and arm 3. The slide may be held in the guide opening by slight friction so as to be capable of being readily slide to engage the cutter teeth.

In operation, the arms 1 and 2 are engaged with the cutter teeth and due to the right-angular relation thereof, the device may be used with cutters of varying diameters. The slide is then moved to engage the points of the teeth and the angle of clearance of the latter thus determined.

By providing two or more of the slides, each of which may be used with the same body of the gauge, the range of use of the gauge may be widened accordingly. It will also be noted that the arm 3 and the guide 4 conjointly form a handle in setting and holding the gauge on the cutter teeth.

Having thus described my invention, what I claim as new and desire to secure by Letters Patent is:

1. In a cutter clearance gauge, a Y-shaped body, a fixed guide on the central arm of the body and cooperating therewith to form a handle, and a double ended slide in the guide having its opposite side faces beveled and its ends formed with angularly related gauge edges.

2. In a cutter clearance gauge, a substantially Y-shaped body formed to seat on the teeth of cutters, a guide on the central arm of the body, and a double-ended slide in the guide having angularly related gauge edges on one end thereof movable to lie beyond the crotch of the body.

3. In a cutter clearance gauge, a body having right-angularly related arms formed to seat on the cutter teeth, and a slide carried by the body and disposed centrally between the arms and having angularly related gauge edges on one end thereof movable to lie beyond the crotch of the body.

4. In a cutter clearance gauge, a V-shaped body formed to seat on the teeth of cutters, guide means having open ends fixedly related to the apex arm of the body, and a

reversible slide gauge having each end thereof formed for insertion in the guide means and movable to have the inserted end lie beyond the crotch of the body, so as to 5 align with the space centrally between the legs of the body.

In testimony whereof I have signed my

name to this specification in the presence of two subscribing witnesses.

WALTER F. SMITH.
